UNITED STATES PATENT OFFICE.

CHARLES H. TOMLINSON, OF MANSFIELD, OHIO, ASSIGNOR TO THE TOMLINSON COUPLER COMPANY, OF MANSFIELD, OHIO, A CORPORATION OF OHIO.

SUPPORTING AND CENTERING DEVICE FOR CAR COUPLERS.

Application filed November 21, 1924. Serial No. 751,204.

My invention relates to car coupling devices and to that class of device for supporting and centering the car coupler.

The object of my invention is to provide a device for supporting and maintaining the car coupler in a predetermined position when the cars are in an uncoupled relation and which can be made to engage and disengage with the car coupler at will of the operator.

Another object of my invention is to have the centering and supporting elements moved into and out of engagement with the car coupler substantially simultaneously, and in which their simultaneous operation is automatic.

Another object of my invention is to have the supporting and centering mechanism automatically moved out of or into engagement with the car coupling device on two coupled cars upon opening or closing respectively the air valves controlling the flow of air through the car couplers.

With cars equipped with couplers which operate upon short radius curves, it is necessary to pivotally mount the couplers to swing through quite an angular displacement on either side of the longitudinal center line of the car. Such couplers are often very heavy and require considerable effort upon the part of an operator to move the couplers to a central position, or approximately so, when coupling up two cars. In steam road operation the curves are usually of long radius and angular movement of the couplers is not necessarily great and a centering device which is in operation at all times can be employed.

In the operation of systems in which the coupler is necessarily mounted to have a great lateral swing, it is not practical to have a centering device which is under operation all the time, that is, in which the coupler is constantly operating the centering device whenever the car is operated around a curve. I have, therefore, invented a mechanism in which the centering device is moved out of operative engagement with the coupler upon the coupling of two cars and thereafter at will of the operator. This mechanism also has incorporated with it the movement of the supporting elements out of engagement with the coupler head at will of the operator after two cars have been coupled together. Also, the operation

of the supporting and centering mechanism is so combined and coordinated that the movements of the same out of and into operative relation with the coupler is made simultaneously at the will of the operator.

The majority of cars at the present day are equipped with air brake systems in which each car is provided with air brake mechanism and the air brake mechanism of one car is coupled to that of the adjoining car through the medium of pneumatic couplings made and held in coupled relation by the mechanical or car coupler upon impact of the cars. The opening of the pneumatic system from car to car is usually brought about automatically upon impact of the cars or by hand operation after the car coupling has been made and likewise the closing of the air communication from car to car is made automatically or by hand at the time of uncoupling the cars. I make use of the air pressure in the pneumatic system for operation of my invention, and also couple my invention in with the pneumatic system such that when the pneumatic system on the two cars is completely coupled and in operative relation, my supporting and centering mechanism is out of engagement with the coupler head, but when the communication of the pneumatic system from car to car is interrupted, the centering and supporting mechanism will automatically be brought back into normal operative relation with the coupler head.

While I have stated that my invention is particularly applicable to cars equipped with pneumatic air brake systems, still it is evident that it can be installed and operated upon cars which are not equipped with the air brake system, by installing on the car a pneumatic system suitable for creating the necessary supply of air, but occasions of this nature will be very remote as most cars, as stated, are equipped with the air brake system at the present day.

It will be apparent that when two cars are operating in coupled relation and my invention has been moved out of operative relation with the car couplers, that the couplers are free to move laterally due to the cars swinging around a curve or to move vertically due to the cars operating over a break in grade.

My invention resides in the new and novel construction, combination and arrangement

of the various parts hereinafter described and shown in the drawings accompanying this specification and later set forth in the claims, and it will be apparent to those skilled in the art that many modifications may be made from the preferred embodiment of my invention herein disclosed.

In the drawings:

Fig. 1 is a front view in partial section 10 of my invention shown as supporting a car coupler (in section), as would be the case when my invention was in normal operative relation with the car coupler, on a car in uncoupled relation with respect to another car.

Fig. 2 is a side view of Fig. 1.

Fig. 3 is a side view of two cars in coupled relation and shows the relation of the mechanism to the car coupler after the operator has caused the supporting and centering 20 mechanism to move out of operative relation with the car couplers. This view shows the relation of the parts when in full operative position.

Fig. 4 shows an end view of Fig. 3 taken 25 on the line 4—4 to further show the relation of the centering and supporting mechanism with respect to the car coupler when the cars are in full operative relation.

Fig. 5 is a sectional view on the line 5—5 30 of Fig. 4.

Fig. 6 is a sectional view on the line 6—6 of Fig. 1.

Fig. 7 is a schematic view showing the 35 pneumatic connections from my mechanism to the source of air supply, and manually operated means for controlling the supply of air from one car to the other when the cars are in coupled relation, and to the centering and supporting mechanism.

In the preferred embodiment of my invention, I have shown the same as secured 40 to the structural steel sills 1 of a car body. I have also shown a structural iron cross-beam 2 to which the anchorage member 3 is secured for pivotally attaching the car coupler 4 to the car body.

My invention proper comprises two oppositely disposed air cylinders 5 secured to the 45 steel car sills 1 by means of the bolts 6. Mounted within each cylinder 5 is a piston 7 to which is secured the piston rod 8. To the lower end of the cylinder is threadably secured a cup shaped flange 9 having a central orifice therein through which the piston rod 8 may reciprocate. Between the flange 55 9 and the piston 7 within the cylinder 5 is positioned the spring 10 normally maintaining the piston 7 in its upward or retracted position.

To the lower end of the piston rod 8 is secured a cross-beam 11 for supporting the 60 coupler 4 and for carrying the centering mechanism. This cross-beam comprises two spaced structural steel members 12 entire throughout their length. At each end of

the two members 12 is secured a tubular member 13 secured to the members 12 by means of the bolts or rivets 14.

Positioned at the center of the members 12 and between the same is the central spacing block 15 secured to the members 12 by the through bolts or rivets 16. Secured adjacent the end of the member 13 are lugs 17 to which the end of the piston rod 8 is secured by means of the pin 18 whereby the 70 members 8 and 11 will move upwardly or downwardly simultaneously and also pivot slightly about the pin 18 should there be any tendency for one piston to move more rapidly than the other. The extreme end of the member 13 is provided with two spaced and projecting members 19, and secured to the members 12 by bolts or rivets 20, which in turn secure the member 13 more strongly to the members 12, as the members 19 are in integral part of the member 13. Positioned between the members 19 is a shive or pulley 21 mounted on the cross-pin 22 and about which the pulley 21 rotates. At the extreme upper portion of the projecting members 19 75 is a cross-pin 23 to which is secured a cable socket 24.

Positioned between the members 12, on each side of the spacing member 15 and movable lengthwise of the beam 11, is the reciprocating member 25 which is movable between the spacing member 15 and the adjacent end of the member 13. The member 25 is provided with an upstanding lug 26 to engage with the coupler 4, also projecting support members 27 resting upon the members 12 and also the members 28 engaging with the lower faces of the members 12. The members 27 and 28 act as guide members and means to maintain the reciprocating member 25 in slidable relation with respect to the members 12. The member 25 is provided with a cup shaped opening 66 and there is mounted in this opening 66 and the opening 67 in the member 13 a spring 68 tending normally to hold the member 25 in engagement with the member 15, or at least urging the member 25 to move toward the center of the beam 11. Positioned centrally of the member 25 is a plunger 29 provided with a head 30 normally engaging the member 25. To the rear end of the member 29 is a pin 31 to which is secured the cable socket 32. The sockets 24 and 32 are connected by means of the flexible cable 33. The cable 33 passes over the shives 21 and 34 and is sufficiently long such that when the beam 11 is in its normal upward position the members 25 will be in their normal position adjacent the center of the beam 11. The shive 34 is mounted on the pin 35 which in turn is secured to the spaced lugs 36 upon the cylinders 5.

The springs 10 and 68 should each be strong enough to perform its individual

function, that is, the springs 10 should be sufficiently strong to raise the beam 11, with the coupler resting thereon, to the normal position of the coupler, as shown in Fig. 1, and either spring 68 should be sufficiently strong to move the coupler to the central position when the coupler is resting upon the beam 11 and out of center. If the springs are stronger than necessary to perform their individual functions, it will be apparent that one spring will tend to assist the other in performing its function.

By means of the cable connections, as shown, the member 25 will be moved twice the distance that the piston 7 moves and this is of advantage for the reason that the lateral movement of the coupler when in coupled operative relation with another car is liable to be very much greater than the vertical movement of the coupler, therefore, a construction in which the centering elements move a greater distance from the supporting element is of advantage.

The coupler head 4, as shown, is provided with a trough like member 37 which rests directly upon the members 12 and the members 26 are made of sufficient height such that they will engage with the member 37 should the coupler heads swing too far in either lateral direction when two cars are coupled together. By making the members 26 to be engaged by the member 37, if the lateral swing of the coupler is excessive, such construction prevents the accidental positioning of the coupler on the side of the member 26 toward the cylinders 5 and at the same time permits an excessive swing of the coupler body, further compressing the spring 68 and until the adjacent ends of the members 13 and 25 meet or the spring 68 fully compressed. It is quite apparent that relative movement of the various parts is a matter of design to meet the requirements of actual practice and may vary under varying conditions.

The operation of my invention is brought about by supplying to the cylinder 5 air pressure from the fluid-pressure system. In Fig. 7 is shown schematically a coupler 4 pivotally mounted at 3 to pivot longitudinally along the supporting beam 11 which is supported by the pistons and springs contained within the cylinders 5. There is also shown a reservoir 38, which may be the usual reservoir of the brake system, and which is supplied with air from an air compressor through the pipe 39 leading into the pipe 40. As illustrated, I have shown two fluid-pressure lines 41 and 42 positioned above and below the coupler 4 respectively, and terminating in the face thereof at 43 and 44 respectively. The line 41 I have shown as connected to the reservoir 38 through the hose connection 45, piping 46 and 40. The fluid-pressure line 42 is connected by means

of the hose 47 and piping 48 and 49 to the air brake control system. The flow of air through the pipes 41 and 42 is controlled by means of the valves 50 and 51 respectively, which are connected by a common shaft 52 to which is connected the operating handle 53. From the pipe 46 leads a pipe 54 which in turn leads to the branch pipes 55 and 56 and one of these branch pipes leads to one cylinder 5 and the other branch pipe leads to the other cylinder 5.

It will be apparent that if two cars are standing in an uncoupled position, that the relation of the coupler and supporting and centering mechanism will be as shown in Figs. 1 and 2. If these cars are brought together, the air connectors 43 and 44 on the two cars will be brought into coupled relation by impact and the cars, together with the air couplers, will be held in coupled relation by the interlocking hooks 57. My car and air coupler may be of such a construction as shown in my Patent No. 1,094,612, issued April 28, 1914, or of other suitable make. As soon as the two cars are brought together and coupled, the operator will then move the handle 53 so as to complete communication from car to car through the couplers 4 and simultaneously therewith air pressure will flow to the cylinders 5 and force the pistons and piston rods therein downwardly against the tension of the springs 10, and will simultaneously and automatically therewith cause the members 25 to move away from the center and the beam 11 to move downwardly thereby leaving the connected couplers free of the supporting and centering mechanism.

When it is desired to uncouple the cars, the operator will move the handle 53 in the opposite position so that the valves will take the position shown in Fig. 7. This will cut off the air communication from car to car through the couplers 4, and will also relieve the pressure in the cylinders 5 through the relief port 58 in the valve 50, and this will permit the springs 10 and 68 to perform their function of returning the supporting and centering mechanism to its normal position. This having been done, the operator will then proceed to separate his cars. If the cars are operated on a curve the position of the coupler will be to one side of the longitudinal center line, but when the couplers are mechanically uncoupled, one of the members 25 through the operation of the springs will move the coupler to its central position, as shown in Figs. 1 and 2.

It will be apparent that should the cars break apart while moving under normal operating conditions, that the air will be released from the cylinders 5 through the pipes 55 and 56 respectively, through the pipe 54, the hose 45 and the pipe 41 to atmosphere, and the supporting mechanism

will function automatically to support and position the coupler on each of the cars, and if the air system is operating air brakes with automatic setting, the brakes will be subject to an emergency application and the cars automatically stopped.

I have shown the simplest form of operating mechanism, that is, hand operated valves 50 and 51, which, of course, will require operation in each of two coupled cars in order to fully complete the air connections from car to car although the operation of the valves 50 and 51 on one car supplied with air pressure will be sufficient to operate the centering and supporting mechanism on the two cars, as they are both connected to pipes between the valves 50 on two cooperating cars. However, the valves 50 and 51 may be operated simultaneously on both cars, as shown in my Patent No. 1,223,223, issued April 17, 1917, and thereby completing the coupling operation on two coupled cars and moving the centering and supporting mechanism to its coupled position, as shown in Fig. 4, by an operator positioned in one of the cars, or vice versa.

While I have described the operation of my invention in connection with pneumatic or air pressure derived from the air brake system or an independent source of air supply, it will be evident that my invention can also be operated by other fluid-pressure means than air, as for instance, an oil may be used or other liquid which will not thicken or freeze in cold weather, as for instance, certain grades of lubricating oil or castor oil which, under some circumstances, is mixed with a thinner which will not freeze, such as alcohol, or a non-freezing water solution may be used comprising water mixed with a sufficient quantity of alcohol. In the use of liquids, such as oils, water, etc. the proper apparatus for securing the necessary pressure would be required, but these are old and well known in the arts in connection with hydraulic systems of various sorts. When a liquid pressure is used to operate my invention, the port 58 will be connected back to the compressing apparatus in place of discharging to the atmosphere so that the fluid medium could be used over and over, otherwise the system would be very expensive. Therefore, I do not wish to be limited to the use of air or pneumatic pressure as the operating medium for my invention.

I claim:

1. A combined supporting and centering device for couplers comprising mechanism for moving the supporting and centering elements either into or out of operative relation with the coupler.

2. A combined supporting and centering device for couplers comprising mechanism for moving the supporting and centering

elements either into or out of operative relation with the coupler substantially simultaneously.

3. A combined supporting and centering device for couplers comprising fluid-pressure operated mechanism for moving the supporting and centering elements out of operative engagement with the coupler.

4. A combined supporting and centering device for couplers comprising fluid-pressure operated mechanism for moving the supporting and centering elements out of operative engagement with the coupler and spring operated mechanism to move the centering and supporting elements into operative relation with the coupler.

5. A combined centering and supporting device for couplers comprising mechanism operating to move the centering elements away from each other and simultaneously move the supporting element away from the coupler.

6. A combined supporting and centering device for couplers comprising a spring held support for the couplers, spring held centering elements mounted upon the support and fluid-pressure operated means to move the centering elements away from their central position.

7. A support for a coupler comprising in combination a support element, fluid-pressure operated means to move the support element out of operative relation with the coupler and spring operated means to move the support element into operative relation with the coupler.

8. The combination with a support for a coupler, of a fluid-pressure operated means to move the support out of operative relation with the coupler and spring operated means to move the supporting element into and maintain it in operative relation with the coupler.

9. The combination with a spring held centering device for a coupler, of fluid-pressure operated means to move the centering device out of operative relation with the coupler.

10. A centering device for a coupler comprising in combination, a support element, centering elements mounted thereon and holding the coupler central and fluid-pressure operated means to move the centering elements away from the coupler.

11. A centering device for a coupler comprising in combination a support element, spring held centering elements mounted thereon and yieldingly holding the coupler central and fluid-pressure operated means to move the centering elements away from the coupler.

12. The combination with a centering device for a coupler, of a fluid-pressure operated means to move the centering device out of operative relation with the coupler.

13. The combination with a centering device for a coupler, of means to move the centering device either out of or into operative relation with the coupler at will. 10
- 5 14. The combination with a spring held centering device for a coupler, of means to move the centering device either out of or into operative relation with the coupler at will. 10
- 10 15. A combined supporting and centering device for couplers comprising in combination, a supporting means and centering means mounted thereon and means to move the supporting and the centering means out 75 of operative relation with the coupler. 80
- 15 16. A combined supporting and centering device for couplers comprising in combination, a supporting means and centering means mounted thereon and means to move 20 the supporting and the centering means out of operative engagement with the coupler, the movement of the centering means being not less than twice that of the supporting means. 85
- 20 17. The combination with a car and air coupling system for two cooperating cars comprising a plurality of fluid-pressure connections through the coupling devices of fluid-pressure operated means on each car to 90 support and center the coupler, means on each car to control the fluid-pressure connections and to control the operation of the supporting and centering means either out of or into operative relation with the coupler 95 at will of the operator. 95
- 25 18. The combination with a car and air coupling system for two cooperating cars comprising a fluid-pressure connection through the coupling devices, of fluid-pressure operated means on each car to support and center the couplers when uncoupled 100 fluid connections to the fluid pressure operating means, means on each car to open or close the fluid-pressure connections and means to inter-connect the fluid-pressure connections to the fluid-pressure operated means and the fluid-pressure connection through the couplers to move the fluid-pressure operated means on each car away from the couplers 105 when the fluid-pressure connection through the coupling devices is open and vice versa. 110
- 30 19. In a car and fluid-pipe coupling system on two cooperating cars, the fluid-pipe connections being on the faces of the car 115 couplers, fluid-pressure operated means on each car for supporting and centering the couplers on the cars and means on each car to control the fluid-pipe connections and operate the fluid-pressure operated centering and supporting means on both cars when the controlling means for the fluid pipe connections on both cars have been operated. 120
- 35 20. In a car and fluid-pipe coupling system for two cooperating cars, means to control the fluid-pipe connections, means to cen- 125 ter and support the couplers at the time of coupling the cars and means operated from the fluid-pipe system to automatically move the centering and supporting means out of operative relation with the couplers. 130
21. In a car and fluid-pipe coupling system for two cooperating cars, means on each car to control the fluid-pipe connections, means on each car to center and support the couplers at the time of coupling the cars 75 and means on each car operated from the fluid-pipe system to automatically move the centering and supporting means on both cars out of operative relation with the couplers. 80
22. A system of fluid-pipe coupling for two cooperating cars comprising a fluid-connection through the coupling devices, means on each of the cars for supporting and centering the coupling devices and 85 operated by fluid-pressure to move out of operative relation with the coupling devices after the coupling of the cars has been effected, devices on each of the cars to control the fluid-pipe connections and the supporting and centering means to open or close the fluid-pipe connections on one car and simultaneously move the centering and supporting means on both cars out of operative relation with the coupling devices and other 90 means to move the centering and supporting means into operating relation with the coupling devices. 95
- 25 23. In car and fluid couplers, the combination with a mechanical coupling which is 100 interlocked upon impact of the coupler heads, of fluid connecting means engaged upon impact and air circuits leading therefrom and cooperating with corresponding parts when the mechanical coupling is made, 105 means to support and center the couplers and means controlled by manual operation for simultaneously completing the fluid connection through adjacent coupler heads and moving the supporting and centering means 110 out of operative relation with the couplers after the mechanical coupling has been made. 115
- 28 24. The combination with a car and air coupling device of a supporting and centering mechanism therefor, fluid-pressure operated means to move the mechanism out of engagement with the coupling devices and means to control the operation of the pneumatic means. 120
- 30 25. The combination with a car and air coupling device having a universal connection with a car body and adapted to maintain alinement with a cooperating coupling device when coupled, of a supporting mechanism therefor, fluid-pressure operated means 125 to move the mechanism out of engagement with the coupling devices after they are in coupled relation and means to control the operation of the fluid-pressure means. 130
- 35 26. A supporting and centering mecha- 135

- nism for a coupler pivotally mounted to swing laterally comprising supporting means for the coupler, centering means for the coupler, means to move the supporting and 5 the centering means out of normal operative engagement with the coupler, the centering means arranged to be engaged by the coupler if the coupler swings beyond a predetermined distance.
- 10 27. A centering mechanism for a coupler pivotally mounted to swing laterally, comprising centering means to move the coupler to its central position, means to move the centering means out of normal operative engagement with the coupler, the centering means arranged to be engaged by the coupler if the coupler swings beyond a predetermined distance.
- 15 28. A supporting and centering device for
- couplers comprising a horizontally mounted 20 supporting bar, a fluid-pressure operated piston mounted in a cylinder at each end of the bar and adapted to be suspended from the car body, means connecting the pistons to the ends of the bar, a spring in each cylinder 25 to maintain the pistons in their upper positions, means to admit air to the cylinders above the pistons to move them downward, centering members mounted on the bar to move longitudinally thereof, springs acting upon the centering members to move them toward each other and into operative relation with the coupler, means connected to the centering members to move them away from each other when the bar is moved 30 downward.
- 35 In testimony whereof I affix my signature.

CHARLES H. TOMLINSON.
